Dec. 815

Rufel Wheeler & Stephen A. Bailey of Utica, N. Y.
Letters Patent No. 815, Dated July 8th 1856

The Schedule referred to in these Letters Patent, and making part of the same.

To all whom it may concern:

Be it known that we, Rufel Wheeler and Stephen A. Bailey of the City of Utica in the County of Oneida and State of New York, have invented or produced a new and original design for a parlor-oven or cooking stove, called the "Parlor oven," and we hereby declare that the following is a full and exact description of the same, reference being had to the accompanying drawings of the same.

Letter A, is the movable perforated top.

B, B, the oven doors.

C, door to the fire chamber

D, the bottom or hearth plate.

E, the damper

F, F, F, the feet

G, the middle plate

H, the top plate

I, the front plate

What we claim as our invention or production and desire to have secured by Letters Patent, is the general design and configuration of the stove.
